UNITED STATES PATENT OFFICE.

ELMER S. STACK, OF WEST SOMERVILLE, MASSACHUSETTS.

WATER-HEATER.

1,306,197.

Specification of Letters Patent. Patented June 10, 1919.

Application filed January 23, 1914. Serial No. 813,905.

To all whom it may concern:

Be it known that I, ELMER S. STACK, a citizen of the United States, and resident of West Somerville, in the county of Middlesex and State of Massachusetts, have invented certain new and useful Improvements in Water-Heaters, of which the following is a specification.

The present invention relates to a heater for heating water or other fluids, in which I have incorporated two principal important and novel features of improvement, one of these being the provision by which the incoming cold water is given a preliminary 10 degree of heating by the already heated water in the heater before entering the portions of the heater which are directly exposed to the products of combustion arising from the burner or other heating agent; 15 and the other of which is the arrangement of the parts of the heater in such a way as to cause a continuous circulation of the fluid to be heated whether any of the fluid is being drawn off or not, and the location 20 of a thermostatic heat-controlling device in a part of the heater which is shielded to some extent from the direct heat of the heating agent, but in such a way that the heat-controlling device is exposed to the incoming 25 fluid and to the circulating fluid when there is no withdrawal from the heater.

The importance of the first of these features becomes apparent when it is realized that in water heaters, and particularly those which are heated by the flame from a gas burner, a great deal of trouble has been experienced by condensation of water from the products of combustion on the parts of the heater which are exposed to the 35 flame. In all the heaters of this character heretofore produced, so far as I am aware, the water or other fluid to be heated is caused to flow from the main directly into a coil or into tubes which are exposed directly to the products of combustion rising 40 from the burner. These products contain a considerable proportion of water vapor, part of which is produced by combustion of the fuel and part of which is present in the 45 air furnished to support combustion. The water which enters such coils or tubes is frequently, and usually, at a low enough temperature to cause condensation of this water vapor, which gathers on the tubes and drips upon the burner, checking the flame 50 and causing rapid deterioration of the burner.

itself by corroding the metal of which it is composed. My invention avoids this effect by first bringing the cold incoming fluid into thermal contact with the already heated 60 fluid in the heater, before allowing it to pass into those tubes which are directly exposed to the flame, and maintaining such thermal contact for a period long enough to heat the incoming fluid to a temperature 65 higher than that which causes condensation of the water vapor in the products of combustion.

The other feature of the invention secures improved results in maintaining an even 70 temperature in the fluid in the heater, in enabling the heater to respond quickly to demands for the heated fluid, and in effecting a marked saving in the use of fuel or other heating agent, enabling such heating 75 agent to be used with the greatest efficiency and without waste.

A heater containing my inventions may be used in any situation where the necessity for supplying heated fluids exists. It is 80 particularly adapted to those situations where instantaneous hot water is demanded and the demand for the same is relatively infrequent, so that it would not be the best economy to employ a supply tank in connection with the heater. It is to be understood, however, that in thus specifying a particular situation for which the present improved heater is particularly adapted, I do not thereby intend in any way to indicate a limitation in the use of the heater or in the scope of the invention, since the principles of my invention are applicable to all places and conditions in which a heater for fluid may be necessary or useful. 85 As heaters of the type to which my invention is here shown as being applied are mainly used for heating water, I shall in the following description refer to the fluid acted upon as being water, making it distinctly understood that the fluid is thus characterized for convenience of description only and not with any limiting significance. 90

In the accompanying drawings I have illustrated embodiments of the above described features of my invention adapted for various particular uses, without thereby intending to imply any limitation of the invention to the forms or embodiments illustrated.

Figure 1 is an elevation of the exterior of one form of the heater.

Fig. 2 is a vertical central section of the heater shown in Fig. 1.

Fig. 3 is a modified form of heater embodying the essential principles illustrated 5 in Fig. 2.

Fig. 4 is an elevation of a coil adapted to form part of the heater and embodying another form of means from that illustrated in Figs. 2 and 3 for producing 10 thermal contact between the incoming water and the heated water.

Fig. 5 is a sectional view on a larger scale of a part of the coil shown in Fig. 4.

Fig. 6 is a sectional view illustrating 15 the principles of the invention applied to a series of heating units.

The same reference characters indicate the same parts in all the figures.

Referring first to Figs. 1 and 2, 1 represents the water tubes through which the 20 water flows while being heated and 2 represents a gas burner for generating the heat for heating the water. The tubes 1 pass between upper and lower headers 3 and 4, respectively, which are preferably shaped 25 somewhat as hollow cones. The construction and arrangement of headers and water tubes is preferably substantially that shown in my Letters Patent of the United States 30 for water heater, numbered 1,125,758, and granted January 19, 1915, the tubes 1 being set into the conical faces of the headers and firmly secured therein, and extending from one header to the other in nearly vertical 35 lines, but somewhat offset laterally and angularly about the axis of the heater in order more effectively to intercept the ascending currents of hot gases from the burner. The headers are connected together centrally 40 within the cluster of tubes 1 by a central tube or conduit 5 which is sufficiently large to permit of free flow of water and to contain a thermostatic element as will be presently explained.

45 In the preferred construction the cold water inlet and the hot water outlet are formed in a single connection 6 which has a coupling portion 7 attached to the upper header, an inlet coupling 8 with which the 50 cold water supply pipe 9 is connected, and an outlet coupling 10 with which the hot water delivery pipe 11 is connected. An inner elbow-like conduit 12 is formed in the connection in communication with the inlet 55 8 and is turned toward the header 3, being furnished with an extension 13 which extends well into the header and preferably into the central connecting tube 5. The conduit 12 and its extension 13 are of such dimensions and so located that a sufficiently 60 wide space is provided around them in the connection 6 to permit free outflow of the heated water without material impedance.

The conduit 14 for supplying gas to the 65 burner passes across the heater below the

lower header and is connected with or contains a valve casing 15 which is crossed by a partition 16 having an aperture surrounded by a valve seat. A valve 17 co-operates with said valve seat and is normally 70 held seated by a spring 18 which bears against the valve and abuts on a cap 19 which closes the cavity or branch of the valve casing in which the valve and spring are contained. A frame 15^a is connected 75 with the valve casing and supports the mechanism whereby the thermostat operates the valve with an accelerating motion. This frame is connected by a tube 20 with the lower header. In the tube is screwed a plug 21 wherewith is connected a thermostatic 80 tubular element, or tube 22, smaller than the tube 20 and located within the latter, made of copper or any other suitable material which has a sufficiently great coefficient of 85 expansion. This thermostatic tube passes through the lower header and into the tube 5 toward the water inlet conduit 13. Preferably the thermostatic element extends 90 through as great an extent of the heater as possible so that a considerable motion of the free end of the element may occur with changes in the temperature of the water, and is also arranged so that it is thermally 95 acted upon directly by the incoming water. The end of the thermostatic element is closed, and acts upon the end of a rod 23, which may be of carbon, steel, or of any other sufficiently hard material having a sufficiently low coefficient of expansion. The 100 rod 23 bears on a lever 24 pivoted at 25, and acting through an antifriction roll 26 on a lever 27 pivoted at 28. The lever 27 carries a stem 29 which bears on the stem 30 of the valve. Stem 29 is adjustable, being screwed into an internally threaded socket in the arm 27, which socket is divided and its branches are clamped against the stem 29 by a clamp screw 31, to maintain the adjustments. As 105 will be readily understood the adjustments of the stem 29 determine the temperature which is given to the water in the heater, by hastening or retarding the opening of the valve.

A pipe 32 leads from the valve 15 and is 110 conducted in any manner suitable to the flaring admission end of a draft tube 33 which conducts mingled gas and air to the burner 2. A pilot burner 34 is connected to the gas conduit 14 on the supply side of the 115 control valve 17.

The operation will be readily apparent from an inspection of the drawings in connection with the foregoing description. The cold water which enters the heater when hot 120 water is drawn therefrom, issues directly against the thermostatic element and flows through the relatively narrow space surrounding the thermostatic element in the tube 5 before it enters the heating tubes 1. 125

In this way the thermostatic tube is exposed throughout its whole length to water at substantially the temperature of the supply. The consequent contraction of the thermos 5 static element causes the valve 17 to be opened widely and to produce a hot flame at the burner. The course of the water after issuing from the extension 13 of the inlet conduit is downward through the tube 10 5 into the lower header 4 and thence upward through the heating tubes 1 to the upper header 3. In passing through the tubes 1 the water is sub-divided into small 15 volumes and is rapidly heated, being delivered to the upper header at the desired temperature. Thence it flows through the connection 6 in the annular space surrounding the inlet conduit 12 and extension 13 and so to the delivery pipe.

20 When the demand upon the heater is equal to the fuel supply capacity of the heater the water circulation is that described, and the thermostatic element is exposed to the lowest temperature possible and the flame at 25 the burner is turned up to the maximum extent. When the demand for hot water is reduced, the hot water is not able to pass out from the connection as rapidly as it enters the header 3 from the tubes 1; and when 30 there is no demand for hot water at all there is no escape for the heated water. In each case a gravity thermal circulation is set up, in the course of which the water exposed to heat in the tubes 1 rises, and enters the header 3, while the cooler water in the header 3 and tube 5 naturally flows downwardly through the tube 5 to the header 4 and thence to the tubes 1. This circulation continues when any flame is produced at the 35 main burner 2 or at the pilot burner 34, and has the effect of heating the water in the tube 5 and expanding the thermostatic element 22, relieving the pressure which tends to open the gas valve 17 and allowing such 40 valve to become partly or wholly closed, according to the temperature.

In this apparatus the pilot flame produced at the burner 34 has a function additional to that of igniting the flame at the main burner 50 when the valve 17 is opened. This additional function is to supply heat to the heater sufficient to maintain the thermal circulation described and to maintain the temperature of the heater at that degree at 55 which the thermostat keeps the valve closed. If the heat of the pilot flame should not be sufficient for this purpose and the water in the heater cools off, the thermostat contracts and opens the main burner valve, furnishing 60 more heat until the predetermined temperature is again given to the water. When the heater is to be out of service for a considerable period of time, the gas supply to both the main burner and the pilot burner 65 may be shut off by a cock 35 in the gas main.

It will be noted that the thermostat is contained in a part of the heater which is not directly exposed to the heat of the flame, but is shielded to a considerable extent from the flame by the outer enveloping tubes 1. These 70 tubes being preferably arranged in three or more enveloping series, as in my patent hereinbefore referred to, intercept and absorb a great proportion of the heat delivered by the burner. Not only is the portion of the heater 75 which contains the thermostat thus shielded from the direct heat, but the thermostat within such portion of the heater is further protected from direct heat by the body of water in such portion, which may be relatively very large, and considerably larger than illustrated in the drawing. Even without changing the location of the tubes 1, the part 5 of the heater could be made of greatly increased diameter, and the diameter of this 80 part could be further increased by somewhat altering the positions of the tubes 1 without departing from the principle of the invention. Further the thermostat is so located, as above described, that it is surrounded by the coldest water in the heater, 85 namely the entering water, so that the thermostat is heated and caused to act not by the direct heat of the burner or heating agent, but by the circulation of water induced by 90 thermal action.

It will be noted that the inlet for the cold water passes through the water in the header 3. Thereby the incoming water is brought into thermal contact with the hottest water 100 in the heater. If desired an obstruction or baffle may be placed in the tube 13 to retard the flow of water through the same and thereby prolong the thermal contact. Fig. 2 shows a helical baffle 36 which provides a 105 winding passage within the tube 13. This obstruction may be of any length, or it may be entirely omitted, and the tube may be shortened so as to permit an actual mingling of the cold water with the heated water before 110 passing into the central tube 5. In any event the heater is so designed that the cold water becomes somewhat heated before entering the tubes 1, which tubes are the portions of the heater exposed to the products 115 of combustion rising from the burner, so that when the water enters these tubes it will be at a higher temperature than that which would cause condensation of the water vapor in the products of combustion. By this 120 means the highly objectionable effect which is so common in gas water heaters, namely that of condensation of water on the tubes or coils, is avoided.

While the heater as above described and 125 herein illustrated is the one which at present I consider preferable, yet I do not limit the invention here claimed to the details here shown and illustrated. For example, the particular connection 6 while highly prac- 130

tical and very useful and desirable is not the only form of connection by which the cold water may be admitted and the hot water withdrawn from the heater.

5 Separate connections for the hot and cold water, respectively, might be employed without departing from my invention. Neither is it an essential feature of the invention that the thermostat should be fixed in the 10 bottom of the heater and project upwardly. It is equally within the contemplation of my invention to mount the thermostat in the top of the heater, and it may be so mounted without departing from the spirit of the invention provided it is exposed to the water in that part of the heater where the temperature changes of the water are the greatest and most rapid.

It will be apparent that the regulation of 20 the supply of gas to the heater is in proportion to the demands upon the heater, since the temperature in the tube 5 varies according to the rate at which the hot water is drawn off and the cold water enters, and 25 the thermostatic element in such tube is correspondingly elongated or contracted. It is evidently possible therefore by suitable regulation to enable the heater to deliver water at a certain definite temperature in any quantities up to its maximum capacity, and also to 30 alter the temperature at which the water is so delivered.

Fig. 3 illustrates a modification of the heater shown in Fig. 2, in which the thermostat is contained in a tube 51 external to 35 the heater proper. As before, the heater consists of tubes 1, headers 3 and 4 and a central tube or column 5. The latter, however, need not be a conduit for water, but 40 may be so made as only to perform the function of holding the headers and tubes 1 in proper relation to one another. The incoming cold water enters through a tube 91 contained in and passing through the header, 45 such tube being preferably formed into a coil within the header so as to prolong the thermal contact between the tube and the hot water in the header. The discharge end of tube 91 passes into a pipe or thimble 92 50 connecting the tube 51 with the upper header. The lower end of tube 51 is connected with the lower header by a lateral tube 92 and an upright tube 93. The burner 2 is indicated by dotted lines. In this embodiment the thermostat and the position of the controlling valve are reversed from the arrangement shown in Fig. 2. The controlling valve casing 151 is fixed to the upper end of tube 51, and the latter tube contains 55 a plug 211 to which the thermostatic element or tube 220 is secured. The lower end of this thermostatic element is the movable end and is the one which is closed and which acts upon the less expansible rod 230. 60 This rod is shown as directly connected to

the gas controlling valve 171, but obviously a system of accelerating levers could be introduced between the rod and the valve in substantially the same manner as illustrated in Fig. 2. Otherwise the gas controlling 70 valve and the connection from the same to the burner are substantially the same as illustrated in Figs. 1 and 2. It is to be noted that a space is provided between the end of tube 91 and the walls of the connection 75 92. This space provides for a free thermal circulation of water when no water is being either withdrawn from or admitted to the heater. Such circulation is produced by the heated water rising in the tubes 1 and 80 by the cooler water in the tube 51 descending. This embodiment of the invention also contains the described features of my invention, comprising a means for heating the incoming water before admitting it to the 85 tubes which are directly exposed to the flame, and therefore avoiding condensation upon such tubes; and a thermostatic control device which is exposed first to the incoming water, and past which there is a continuous circulation of water whether hot 90 water is being drawn from the heater or not. In this case also the thermostat is not in the part of the heater which is exposed to the direct heat of the burner, but is outside of 95 such part. Although I have not shown the external casing of the heater in Fig. 3, it is part of my contemplation either to mount the tube 51 entirely outside of the casing, or if desired, to interpose a shield between the 100 flame from the burner and the tube 51, in that case keeping the tube within the main casing.

Figs. 4 and 5 illustrate the application of that feature of the invention which relates to 105 preheating the entering water, in a heater of the coil type. Here a coil 37 of any ordinary or other preferred character is provided and is intended to be contained in a casing over a burner, designated 2 and indicated by dotted 110 lines in Fig. 4. The lower portion 38 of this coil is compound, consisting of an inner tube or conduit 39 and a jacket 40. The cold water flows through the inner tube 39, to the lower end of which it is delivered by the admission pipe 95, passing from the jacket to the upper end of the coil 37 through a conductor 41 which is joined with the upper end of the jacket 40 at 42. Then the flow 115 through the coil continues from the top to 120 the bottom, the water coming into thermal contact with hotter and hotter gases and receiving its final degree of heat in the jacket 40 directly over the flame. The hot water delivery pipe 110 is connected with the lower 125 end of the jacket 40. The cold water entering the coil passes first through the pipe within the jacket, which is immediately over the burner and contains the hottest water in 130 the coil. Thereby the incoming water is

heated by thermal contact with the hot water to a degree too high to cause condensation of the water vapor in the products of combustion, and passes through the coil 37, where 5 it is further heated, finally flowing through the jacket 40 directly over the burner and out to the delivery pipe. It will be evident that the arrangement last described embodies the feature of my invention which 10 involves preheating the entering water by the already hot water in the heater before the incoming water is admitted to that portion of the heater which is directly exposed to the products of combustion of the heating agent 15 rising from the burner.

A heater having the characteristics hereinbefore described lends itself to use in various combinations for quickly heating large and greatly varying amounts of water with a little 20 expenditure of gas. For instance, a number of such heaters may be coupled in series, the cold water from the main being delivered to the first of the series, the hot water discharged from this heater being connected 25 to the inlet of the next heater, and so on, until the outlet of the last heater is coupled to the delivery pipe. Such an arrangement, embodying a thermostatic control for each 30 heater and provisions for preheating the incoming water is illustrated in Fig. 6. This heater, or heating series, contains three heating elements 100, 101, and 102, each being preferably, although not necessarily, a duplicate of the heater shown in Fig. 2. Each 35 heater has its own burner, fuel supply valve, and thermostatic regulator, which may be identical with the corresponding elements shown in Fig. 2, or with those shown in Fig. 3, or may be otherwise made or modified 40 without departing from the spirit of the invention. Thermostatic elements for the various heaters are indicated at 221, 222, and 223. The water to be heated is delivered by a pipe 96 which passes into the first heater 45 100 in the manner illustrated in Fig. 2. The circulation in this heater is as already described in connection with Fig. 2, and the hot water passes through a connection 60 which has a branch 61 coupled to a pipe 62 50 leading to a coupling 63, which may be of the same character as the coupling 6 shown in Fig. 2. A branch 132 leads into the second heater in which the water circulation takes place as before, and from which the 55 water now further heated passes through the outlet 64 of coupling 63 to a similar coupling 65 connected with a third heater. The outlet of the last coupling is joined to a pipe 110 having a nipple 111 with which the delivery 60 pipe is connected. The inlet pipe 96 passes through the hot water conduit 110 and is given a preliminary degree of heating by the hot water therein, being raised as in the embodiments of the invention previously 65 described, to a degree at which it will be too

warm to condense the water vapor in the products of combustion generated from the burner of the first heater. A baffle or obstruction 360 may be provided in the inlet pipe 96 to prolong the thermal contact, and 70 such obstruction may be of any length or may be omitted entirely as circumstances warrant.

A heater of the sort last described contains all the principles and advantages 75 hereinbefore discussed, besides having the additional advantage of meeting widely varying demands and furnishing greatly varying quantities of hot water at the desired temperature and without waste of the 80 heating agent. The individual heaters of this combination are designed to permit the maximum rate of flow required of the conditions in which the apparatus is installed, while the burner or heating element of each 85 heater is insufficient to heat the water to the required temperature, when the duty is at the maximum, in any one heater. Under this condition the co-operation of all of the heaters is required to bring the water 90 delivered to the desired temperature, and a portion only of the heat required is absorbed by the water in each heater. The individual thermostatic controls of the various 95 heaters automatically control the amount of heat given by each heater to the water, causing the burner of one or more heaters to be wholly or partially opened according as the demand for heat is greater or less than can be furnished by one heater. 100 Where the demand is very light, one heater running at full or reduced capacity suffices to heat the water to the required temperature and although the water after being thus heated in the first heater passes through 105 the other heaters in succession, its temperature is so high as to cause the thermostatic controls of the other heaters to shut down the flame at the burners of those heaters. Likewise when the demand for heat is 110 greater than one heater can supply but not beyond the capacity of two, the flame at the second heater is turned up owing to the water being insufficiently hot when it reaches that heater, but the flame at the 115 third heater remains shut down. Evidently, therefore, the consumption of fuel is exactly proportioned to the demand for hot water and hot water up to the maximum capacity of the apparatus may be obtained on the 120 one hand, while on the other hand there is no wasteful consumption of fuel to heat a small quantity of water, nor is such small quantity heated to too high a temperature. The apparatus now under consideration is 125 in fact an instantaneous hot water heater capable of furnishing hot water in any quantity or at any rate of flow up to a predetermined maximum, at a predetermined and regulable temperature without varia- 130

tion in temperature, and without wasteful consumption of gas when the demand is light. Under all conditions the fuel is used with the maximum efficiency so as to get the maximum heating effect. At all times the heat developed is regulated by the temperature of the water so that the heat generation is exactly proportioned to the demand, and more or less heat is furnished by turning on or shutting off the gas according as the temperature of the water in the heaters varies, the changes in the heat supply being practically simultaneous with changes in the water temperature.

15 A feature common to all of the forms of the invention in which the hereinbefore described water circulation is possible, is that the pilot flame maintains a moderate heat in the water even when none is being drawn from the heater. The circulation distributes the heat throughout the entire body of water in the heater. This is a factor which conduces greatly to the rapid delivery of hot water when required, inasmuch as the relatively high temperature at which the water is always maintained enables the water to be brought to the desired higher temperature more rapidly than would be possible if this continuous circulation under 25 the heat of the pilot flame did not take place.

It will be apparent from the foregoing description that all embodiments of the invention here illustrated have this feature in common, that they provide means by which the cold water entering the heater is first brought into contact with the highly heated water, and is thereby raised in temperature to such degree that when entering the tubes 30 more directly exposed to the heating agent, it is too warm to cause condensation of water vapor in the products which pass in contact with said tubes. Thus in the form shown in Fig. 2 the tube 13, in that of Fig. 45 3 the tube 91, in that of Fig. 5 the tube 39, and in that of Fig. 6 the tubes 96, 132, and the equivalent of 132 in the heater 102, are interior tubes which are shielded by an outer wall or jacket and the body of hot 50 water contained in said outer member, from the products of combustion. The outer member, wall, or jacket of Figs. 4 and 5 is the jacket tube 40, of Fig. 3 is the header 3, and in Figs. 2 and 6 is in part the header 55 3 and in part the central tube 5 of the headers shown therein. And in each case that part of the heater structure whether it be called a jacket, header or what not, into which the entering water is first admitted, 60 is that which contains the hottest water in the entire heater. Being conducted through such jacket, header, or member in a manner whereby it is shielded from the products of combustion, the entering water cannot chill 65 such products of combustion and such water

before it can arrive in contact with the surfaces which are directly exposed to the products of combustion, is warmed beyond the point at which it would cause condensation. For the purposes of this description the term "inner tube" may be considered as including the tube 13, tube 91, tube 39, tube 96, and tube 132, or any essential equivalent of such tubes; and the term "outer member" as including any sort of a jacket or part such as the jacket 40 or header 3, or equivalent member correspondingly arranged to inclose the inner tube and hold a body of liquid so as to surround the inner tube.

I desire to state that in speaking of the heating element of the heater as a gas burner and of the heating agent as gas, I have not intended to limit my invention to an apparatus in which heat is generated by the combustion of gaseous fuel, neither have I intended to limit the invention to an apparatus in which heat is developed by the combustion of any fuel. In respect to the heat regulator I reserve the right to employ any suitable heater which is subject to control and regulation, whether such heater is a burner for gaseous fuel, a conductor for a previously heated fluid (as steam), the flow of which is controlled by a valve, a fire of any sort controlled by dampers, valves, or screens, or heat generated electrically, under government of any sort of controller capable of being operated by a thermostat.

What I claim and desire to secure by Letters Patent is:

100

1. A water heater for domestic use comprising an inlet, an outlet, a conducting tube into which said inlet discharges and from which the water is displaced by the water entering the inlet when escape from the outlet is permitted, a burner arranged to direct the products of combustion of gas against said tube, and an external container between said tube and the outlet, into which the tube discharges and in which the inlet 110 is contained.

2. A heating apparatus comprising a heating unit having an inlet, a circulating system of tubes and an outlet, a second heating unit having an inlet connected with the outlet of the first heating unit, having a circulating system of tubes and having an outlet, a receiver to which said outlet is connected and to which the heated fluid is delivered and a conductor passing through said receiver and connecting with the inlet of the first heating unit, being so arranged to preheat the incoming liquid before the delivery thereof to the tubes of the first heater.

125

3. A heater including in its construction heating tubes exposed to a heating flame, upper and lower headers to which said tubes are connected, a circulating tube extending from the upper to the lower header, and

130

means for leading the water to be heated through the upper header in thermal contact with the water therein into the circulating tube, whereby the water is warmed before entering the heating tubes, to avoid condensation on the external surface of said heating tubes, of the water vapor contained in the products of combustion of the heating flame.

10 4. A non-condensing heater comprising upper and lower headers, a collection of heating tubes extending between said headers and communicating therewith, a burner arranged to direct products of combustion of burning gas upon said heating tubes, a circulating tube leading from the upper to the lower header and a cold water inlet arranged to direct the incoming water through the upper header into the circulating tube and thence to the lower header and the heating tubes, whereby the water is preheated before entering the heating tube to a temperature above that which causes condensation

of the water vapor in the products of combustion.

5 5. A water heater comprising circulating means through which water is caused to flow in thermal contact with heated products of combustion, a chamber or outer member into which hot water is delivered by said circulating means, and an inlet for water to be heated arranged to cause such water to pass through the interior of said outer member in its course to the circulating means, whereby the incoming water is heated by thermal contact with already heated water in the heater, and before its admission to said circulating means, to a temperature above that at which it would cause condensation of water vapor in the products of combustion. 40

In testimony whereof I have affixed my signature in presence of two witnesses.

ELMER S. STACK.
